BALE TIE

Alvin V. Rowe, Galesburg, Ill.

Application March 21, 1934, Serial No. 716,737

15 Claims.

(Cl. 24—27)

This invention relates to bale ties and more particularly to a type of bale tie capable of use more than one time.

A further object lies in the feature of supporting the loop of the bale tie to prevent collapse as well as to prevent detachment of the tie button when the wire is in a loosened condition.

Other objects will appear in the following specification taken in connection with the annexed drawing in which—

Fig. 1 is a plan view of my bale tie;

Fig. 2 is a plan view with the tie button secured in the loop portion;

Fig. 3 is a sectional view taken on the line 15 3—3 of Fig. 2;

Fig. 4 shows a modification of the supporting means for the loop portion; and

Fig. 5 shows the manner of securing the cross head portion of the bale tie in the loop member having the auxiliary supporting member secured thereto.

Before referring to the drawing, it might be stated that applicant has provided herein a type of bale tie which may be used on more than one occasion. Ordinarily bale ties are used in a single operation and the wire thrown away. The reason for this lies primarily in the fact that the wire either has become so distorted in the ordinary tying operation or the loop has totally collapsed, preventing re-insertion of the tying end of the wire.

Applicant, in Figs. 1, 2 and 3, has provided a bale tie having the main body portion 10. A loop 11 is fashioned thereon with an elongated gripping or wire receiving portion 12.

A spring clip 13 is welded as at 14 and 15 to the loop 11 with its open ends 16 and 17 forming a spring tension closure for the open end of the wire receiving portion 12. The straight end 40 of the main body portion of the bale tie has a plurality of attachment buttons 18 formed thereon, the same being merely upsets or enlargements upon the ends of the wire. These buttons are spaced at a distance of approximately one 45 and one-quarter inches apart.

The above described bale tie has the main advantage of being capable of use more than once. In other words, the bale is tied in the first instance by placing the first button in the wire receiving slot 12 in the manner shown clearly in Figs. 2 and 3. The button is prevented from displacement or detachment from the loop when the wire is in a loosened condition because of the substantial closure of the open end of the member 12 thereof by means of the spring tension

ends of the clip 13. Further, the spring clip by supporting the loop 11 against collapse maintains same in substantially its original shape even when the bale tie is under tension and the wire has been cut for reuse.

It is obvious that in order that the bale tie may be used again, the wire must be cut at a point indicated at 19 and which is a point substantially adjacent the second button 18. Further, it may be seen that after the first button is 10 cut off the same may be readily withdrawn from the receiving portion 12 in the loop and when the bale tie is used for a second time the second button 18 may be inserted within said portion 12 and maintained therein in exactly the same manner as the first button was held.

In the drawing three buttons have been shown, although it is quite obvious that a different number might just as well be formed on the wire. It is understood, of course, that there is a slight 20 variation in the size of bales adapted to be tied, and that the cutting off of approximately one and one-quarter inches of wire on several occasions will not hinder in any way the satisfactory 25 operation of a bale tie constructed in accordance with applicant's design. Further, whenever bales of oversize are tied, the use of splicers is well known and might be used in the usual manner in the type of bale tie disclosed herein.

In Figs. 4 and 5, applicant has shown a somewhat modified means for supporting the loop. In this instance a wire clip 20 is welded to the loop 21 at 22 and 23. The clip further is welded to the wire 24 at 25 and to the main body portion of the bale tie wire 26 at 27. In this instance, 30 the tying end of the wire is formed in a cross-head manner, as indicated at 28. This particular formation of the cross-head is well known and particularly adapts itself for use in combination with a loop supported against collapse 35 in the manner above described.

In Fig. 5 it will be readily seen how the cross-head is secured within the loop and how a portion thereof rests upon the clip member 20.

Experience has shown that bale ties constructed in accordance with the teachings of the present invention may be used at least three times before being discarded. By preventing the loop from collapsing and thereby enabling the buttons to be detached therefrom, the ease with which said ties may be used is greatly facilitated.

What I claim is:

1. A wire bale tie including a main length of wire, a plurality of tie buttons formed along one extremity of said wire, a tie loop provided at the

- other extremity of said wire adapted to interlock with at least one of said tie buttons, and auxiliary means carried by the loop for counteracting the collapsing thereof and for preventing inadvertent detachment of a tie button interlocked with said loop.
2. A wire bale tie including a main length of wire, a plurality of tie buttons formed along one extremity of said wire, a tie loop provided at the other extremity of said wire adapted to interlock with at least one of said tie buttons, and a spring clip element carried by the loop for counteracting the collapsing thereof and for preventing inadvertent detachment of a tie button interlocked with said loop.
3. A wire bale tie having a tie loop and an end for connection therewith, and a clip secured to the loop in a manner to support the loop from collapse.
4. A wire bale tie including a main length of wire, a tie loop provided at one end thereof, a tie button positioned towards the opposite end thereof and adapted to be received and interlock with said loop, a portion of the loop being sufficiently large to normally enable the passage therethrough of said button, and means for preventing the collapse of said last mentioned loop portion in response to the pulling force of the wire.
5. A wire bale tie including a main length of wire, a tie loop provided at one end thereof, said loop including an opening of restricted size and a communicating larger opening, a tie button positioned toward the opposite end of the wire and adapted to be received and interlock with the restricted portion of the loop, and means for preventing the collapse of the larger opening of the loop whereby to prevent the collapsing of said restricted portion.
6. A wire bale tie including a length of wire, a tie loop provided at one end thereof, said loop including an opening of restricted size and a communicating opening of larger size, and means for preventing the collapsing of the larger opening of the loop whereby to prevent the collapsing of the restricted portion of the loop when the wire positioned therein is subjected to a pulling force.
7. A wire bale tie including a main length of wire, a tie loop provided at one end thereof, said loop having a restricted opening and a larger opening communicating therewith, a tie button positioned toward the opposite end of the wire and adapted to be received by and interlock with said loop, and auxiliary means carried by the loop for preventing inadvertent detachment of said button from the restricted portion of the loop.
8. A wire bale tie including a main length of wire, a tie loop provided at one end thereof, said loop comprising a section forming a larger opening and a section having an elongated restricted opening which over its entire extent is at least as wide as the thickness of the tie wire, said restricted opening communicating directly with said larger opening, a tie button positioned toward the end of the wire opposite from the loop and adapted to be received by and to interlock with said loop, and means connected with the loop for preventing inadvertent detachment of said button from said restricted portion.
9. A wire bale tie including a main length of wire, a tie loop provided at one end thereof, said loop having a restricted opening, a tie button positioned towards the opposite end of the wire and adapted to be received by and interlock with said loop, and auxiliary means carried by the loop for preventing inadvertent detachment of said button from the restricted portion of the loop.
10. A wire bale tie including a main length of wire, a tie loop provided at one end thereof, said loop having a restricted opening and a larger opening communicating therewith, a tie button positioned toward the opposite end of the wire and adapted to be received by and interlock with said loop, and supporting means for said larger loop portion for preventing the restricted opening of the loop from becoming smaller when the wire positioned in the loop is subjected to a pulling force.
11. A wire bale tie including a main length of wire, a tie loop provided at one end thereof, said loop having a restricted opening and a larger opening communicating therewith, the sections of the wire forming the loop and positioned on opposite sides of the larger opening being substantially straight and inclined toward each other, and means for preventing the collapsing of said inclined sections of the loop wire when the wire positioned in the loop is subjected to a pulling force.
12. A wire bale tie including a main length of wire, wire-receiving means provided at one end thereof having an opening for receiving the opposite end of said wire, said opening including a restricted section communicating with a larger section, and means associated with the wire stock in the vicinity of the larger section to enable the restricted section to become enlarged at the point where said restricted section communicates directly with the larger section when a pulling force is exerted by the wire connected with the stock in the vicinity of said restricted section.
13. A wire bale tie including a main length of wire, a loop provided at one extremity thereof, the free end of the loop being welded to the main length of wire, and a metal strip welded to the end of the loop which is secured to the main length to support said loop against collapsing.
14. A wire bale tie including a main length of wire, and a loop portion provided at one extremity thereof, the free end of the loop wire being welded to the tie wire proper, and a rigid section forming a connection between the sides of the loop in a manner to secure the loop against collapse.
15. A wire bale tie including a main length of wire, and a loop portion provided at one extremity thereof, the free end of the loop wire being welded to the tie wire proper in parallelism therewith, said loop portion being closed, and a rigid welded section forming a connection between the sides of the loop in a manner to secure said loop against collapse.

ALVIN V. ROWE.
